US0D1099814S

(12) **United States Design Patent** (10) **Patent No.:** **US D1,099,814 S**
(45) **Date of Patent:** **** Oct. 28, 2025**

(54) **PROPELLER WITH STEPPED HUB**

(71) Applicant: **Sharrow Engineering LLC**, Shelby Township, MI (US)

(72) Inventor: **Gregory C. Sharrows**, Shelby Township, MI (US)

(73) Assignee: **Sharrow Engineering LLC**, Shelby Township, MI (US)

(**) Term: **15 Years**

(21) Appl. No.: **30/002,450**

(22) Filed: **May 6, 2025**

Related U.S. Application Data

(63) Continuation of application No. 29/850,786, filed on Aug. 23, 2022, now Pat. No. Des. 1,078,583.

(57) **CLAIM**

The ornamental design for a propeller with stepped hub, as shown and described.

DESCRIPTION

FIG. 1 is a front perspective view of a propeller with stepped hub, showing my new design.

FIG. 2 is a front elevation view thereof.

FIG. 3 is a rear elevation view thereof.

FIG. 4 is a right side elevation view thereof.

FIG. 5 is a left side elevation view thereof.

FIG. 6 is a top plan view thereof.

FIG. 7 is a bottom plan view thereof; and,

FIG. 8 is a rear perspective view thereof.

The broken lines illustrate portions of the propeller with stepped hub that form no part of the claimed design.

1 Claim, 8 Drawing Sheets
